HENRY W. SMITH, OF MENLO PARK, CALIFORNIA

CORNER BRACE

Application filed January 9, 1929. Serial No. 331,219.

My invention relates to a brace suitable for use in a corner or at the juncture of several surfaces where it is desired that the surfaces be maintained in a fixed relative position. It 5 may be advantageously used in connection with wood surfaces and it is in such application that I shall describe it.

One object of the device of my invention is to provide a corner brace which is relatively 10 simple to manufacture.

Another object of my invention is a simple rugged structure of comparatively few parts.

The invention possesses other advantages, some of which with the foregoing, will be set forth at length in the following description, where I shall outline in full that form of my invention which I have selected for illustration in the drawing accompanying and forming part of the present specification. In said drawing I have shown one type of corner brace embodying my invention, but it is to be understood that I do not limit myself to such type, as the invention, as set forth in the claims, may be embodied in a plurality of forms.

Referring to said drawing:

Figure 1 is a plan view of the device of my invention as it appears at one step in its 30 production.

Figure 2 is a perspective view of a corner with a brace of my invention disposed therein.

Figure 3 is a cross section thru an assembled device of my invention.

Figure 4 illustrates another form of the corner brace of my invention with certain additional features of construction.

While the device of my invention may be 40 conveniently formed from various materials I preferably stamp it from a sheet of metal of the desired weight.

As shown in Figure 1, a plate 6 is stamped out in such a shape as to facilitate the fabrication of the device. Thus I preferably form the plate 6 with a trapezoidal outline and, situated at the opposite ends of the base 7 of the trapezoidally shaped plate, I also provide lips 8 and 9 which are preferably rectangular in outline. Preferably I provide

a plurality of teeth 11 which are formed integrally with the plate 6 and extend therefrom at substantially a right angle to one face thereof. Portions of the lips 8 and 9 are removed, preferably by stamping, to provide the slots 12 and 13.

To form the device into a shape suitable for placing in a corner, as in Figure 2, I preferably bend the lips 8 and 9 along the dotted lines 14 and 16, away from that side of the plate 6 from which the teeth 11 project, until they are substantially at right angles to the plate. The lips 8 and 9, together with the corresponding triangular portions 17 and 18 of the plate 6, are then preferably bent along 65 the dotted lines 19 and 21 toward each other and away from that face of the plate 6 from which the teeth 11 project, until the triangular portions are at substantially right angles to the plate. The lips 8 and 9 usually extend 70 toward each other and are in contact with the edge of the plate 6. The lip portions and the plate are then preferably joined by some convenient method as welding.

While I have described the convenient 75 formation of a form of the device of my invention that is suitable for use in corners in which the surfaces are at right angles to each other it is to be understood that the several plates may be so angularly disposed that 80 the device may be used in corners wherein the dihedral angle is other than 90 degrees.

I likewise form, of sheet metal, a staple 85 for use in connection with my device. As illustrated in Figure 1, the preferably trapezoidally shaped sheet 26 is provided with suitable angular extensions 27. These portions 27 are bent back upon the sheet at substantially right angles to form a staple with sufficient distance between the extensions as to 90 permit the ready insertion into the slotted portions 12 and 13 of the body when assembled.

The assembled device is shown in Figure 2 placed in a corner 41 which it is desired to 95 brace. The several teeth 11 are forced into the surface of the wood by some convenient means as hammering so that when finally disposed the plate 6 is in intimate contact with a surface 42 of the corner and the lips 8 100

and 9 are flush with a surface 43 of the corner. To lock the body in this position the staple 26 is now inserted in the slotted portions 12 and 13 of the lips 8 and 9 and driven home with a hammer. The form of the teeth 11 and angular extensions 27 of the staple 26 is illustrated in Figure 3 of the drawing for one form of the device of my invention. The teeth and projections are preferably formed to insure that the device is positioned positively against the surfaces of the corner.

Another form of construction for the teeth 11 and the angular extensions 27 of the staple 26 is illustrated in Figure 4. The plurality of serrations 28 formed on both the teeth and on the staple insure against these projections readily working their way out after being once inserted.

While I have indicated that the lip portions 8 and 9 are joined preferably to the plate 6, this jointure may be omitted, for the device is sufficiently stiff usually without it. The device when assembled and actively positioned in a corner, as in Fig. 2, is so formed that any tendency for the lip portions to vary from their normal position is resisted by the staple 26. Thus, a pressure tending to make portion 9 approach portion 8 is transmitted to the staple 26 and to the several extensions 27 thereof, which are in active contact with the side 43, and by the staple to the portion 8 which is suitably braced to resist deflecting stresses. Likewise a pressure tending to make the portions approach each other is resisted by the staple 26 and the extensions 27 thereof, which are normally in active contact with the surface 43.

I claim:

1. A brace for a corner having surfaces forming a dihedral angle comprising a plate, a plurality of teeth to retain said plate in contact with a surface of said corner, said teeth being formed integrally with said plate and extending a material distance therefrom, a lip integral with said plate and adapted to fit the other surface of the corner, a brace formed integrally with said plate and said lip, a second lip corresponding to said first lip and similarly adapted to fit said other surface of said corner, a brace formed integrally with said plate and said second lip, said lips having perforations therein, and means for retaining said lips in contact with said other surface, said means comprising a relatively slender plate having a plurality of material extensions extending therefrom at substantially 90 degrees thereto and adapted to be disposed thru the perforations in each of said lips to retain said lips in contact with said other surface.

2. A corner brace comprising a single sheet of material bent to form dihedrally spaced sides and integral braces, one of said

sides including approaching but spaced faces, said sheet having perforations in the sides thereof, and a separate staple passing thru said perforations for maintaining the position of one of said sides.

3. A corner brace comprising a substantially single sheet of material bent to form dihedrally spaced sides and integral braces, one of said sides including means formed thereon for forcing the brace into position in the corner, and means for securing the other side.

In testimony whereof, I have hereunto set my hand.

HENRY W. SMITH.
